Attorney

UNITED STATES PATENT OFFICE.

JULIUS BETTIEN, OF BALTIMORE, MARYLAND.

MEANS FOR OPERATING VALVES.

Application filed March 3, 1922. Serial No. 540,765.

To all whom it may concern:

Be it known that I, JULIUS BETTIEN, a citizen of the United States, residing at Baltimore, in the State of Maryland, have 5 invented certain new and useful Improvements in Means for Operating Valves; and I do hereby declare the following to be a full, clear, and exact description of the invention, such as will enable others skilled 10 in the art to which it appertains to make and use the same.

My invention relates to means for operating valves.

Among the objects of my invention 15 are:—

To provide a valve having a movable part comprising a portion adapted for the application of a special wrench thereto, which portion is shaped so that any other wrench 20 applied to said portion will be disengaged by the act of turning, thus rendering it impossible to turn the movable portion without the use of a special wrench.

To provide a valve having a movable part 25 comprising a portion for the application of a special wrench thereto, said portion being so shaped that the special wrench cannot turn said part without the cooperation of a locking mechanism secured to said part and 30 any other wrench cannot turn said part even though the locking mechanism is in place.

These and other objects of my invention 35 will be set forth in the following specification, reference being had to the accompanying drawings, in which:—

Figure 1 is a plan view of my improved valve, the special wrench therefor being shown in place by dotted lines.

40 Fig. 2 is a view of the part shown by full lines in Fig. 1 looking in the direction of the arrow 2 in said figure.

Fig. 3 is a view of the special wrench for use with my improved valve.

45 In the drawings:

5 represents the valve casing which may be made in any approved manner adapted for connection to any desired number of pipes such as 6 which are used to conduct 50 any fluid.

The movable part 7 of the valve may be straight or taper in any approved manner and provided with any number of ports. In the present instance, it is shown tapered 55 and fitting in a conical hole provided in the casing 5. The part 7 is retained in place in

the casing 5 by the washer 8 and nut 9 threaded upon the end of the part 7. The end of the part 7 is riveted over the nut 9 as at 10 in order to preclude the loosening of 60 the nut 9 and the turning of the part 7 by unauthorized persons.

A portion for the application of the special wrench is formed upon the top of the part 7 and said portion consists of the 65 cruciform ribs 11. The ribs 11 have a flat top 12 against which the lock 13 is revolvably secured by the screw 14 which is threaded in the part 7. The lock 13 is also cruciform in shape and has the same contour 70 as the ribs 11. The ribs 11 are beveled as at 15 from the top 12 to where they meet the conical surface of the part 7 in the plane of the top 16 of the casing 5.

The wrench 17 has a hole therethrough 75 bounded by a cruciform surface 18. The surface 18 is of the same contour as the shape of the ribs 11 and lock 13, but is sufficiently larger than either to enable them to readily enter said hole.

80 The operation of my improved means for operating valves is as follows:—

By turning the lock 13 so that the arms thereof coincide with the ribs 11, the wrench 16 can be placed upon said ribs in the position shown by dotted lines in Fig. 1. If the arms of the lock 13 are then allowed to remain in coincidence with the ribs 11 when pressure is applied to the wrench 17, the juncture of the beveled surfaces 15 with 90 the sides of the ribs 11 will act as wedges and raise the wrench 17 from engagement with the ribs 11.

The lock 13 is provided in order to prevent raising of the wrench 17 as just described. After the wrench 17 has been placed upon the ribs 11 the lock 13 is to be turned to the position shown in Fig. 1 and in said position it effectually prevents the disengagement of the wrench 17 from the 100 ribs 11.

It is evident that no wrench applied to the lock 13 can turn the part 7 because said lock is revolvably mounted thereupon.

It is also obvious that no wrench applied 105 to the ribs 11 excepting the special wrench 17 secured by the lock 13 can turn the part 7 because the beveled surfaces 15 effectually prevent engagement of any wrench with said part.

110 While I have shown the ribs 11, lock 13 and surface 18 as cruciform in contour, it

is evident that they may be triform or of any other shape, provided no surface is presented for the application of an ordinary wrench thereto. Furthermore, by riveting the part 7 over the nut 9 as at 10, I insure that considerable power will be required to turn the part 7, and consequently, inadvertent and unauthorized turning of said part will be prevented.

10 Thus it will be seen that I provide a simple, cheap and effective means for preventing unauthorized operation of valves which is capable of wide application, and many changes may be made in my improved valve and the wrench for operating the same without departing from the spirit of my invention.

I claim:—

1. A valve comprising a movable part 20 having a portion shaped for the application of a wrench thereto, surfaces shaped to disengage a wrench from said portion and a lock secured to said part to prevent disengagement of a wrench from said portion.

25 2. A valve comprising a movable part having a portion shaped for the application of a wrench thereto, surfaces shaped to disengage a wrench from said portion and a lock revolvably mounted on said part to pre-

vent disengagement of a wrench from said portion.

3. A valve comprising a movable part having a rib for the application of a wrench thereto, surfaces on said rib to disengage a wrench therefrom and a lock secured to said rib to prevent disengagement of a wrench therefrom.

4. A valve comprising a movable part having a rib for the application of a wrench thereto, surfaces on said rib to disengage a 40 wrench therefrom and a lock revolvably mounted upon said rib to prevent disengagement of a wrench therefrom.

5. A valve comprising a movable part having a rib for the application of a wrench 45 thereto, a casing for said part comprising a top and surfaces on said rib sloping from said top toward the centre of said rib to disengage a wrench therefrom.

6. A valve comprising a movable part 50 having a cruciform rib for the application of a wrench thereto and surfaces on said rib to disengage a wrench therefrom, and a cruciform lock for said wrench revolvably mounted on said part.

In testimony whereof, I affix my signature.

JULIUS BETTIEN.
